TELEPHONE SWITCHBOARD

George Bruce Kamp, Bala Cynwyd, Pa., assignor to International Telephone and Telegraph Corporation

Filed June 23, 1966, Ser. No. 2,789

Term of patent 14 years

(Cl. D26—14)

FIG. 2.

FIG. 3.

FIG. 5.

FIG. 4.

FIG. 1 is an isometric view of a telephone switchboard, showing my new design, the conventional cord member is fragmentarily shown for ease of illustration;

FIG. 2 is a top plan view thereof;

FIG. 3 is a front elevation thereof;

FIG. 4 is a side elevation thereof; and

FIG. 5 is a rear elevation taken at a reduced scale. The dominant features of my design reside in the portions shown in full lines.

I claim:

The ornamental design for a telephone switchboard, as shown and described.
